(57) **CLAIM**

The ornamental design for a pet toy, as shown and described.

DESCRIPTION

FIG. 1 is a front perspective view of the pet toy showing the new design;

FIG. 2 is a front elevation view thereof; the rear view being a mirror image thereof;

FIG. 3 is a left side elevation view thereof; the right side view being a mirror image thereof;

FIG. 4 is a top plan view thereof; and,

FIG. 5 is a bottom plan view thereof.

The broken lines showing are for the purpose of environment and form no part of the claimed design.
